LIFTING JACK

Filed Oct. 11, 1926

UNITED STATES PATENT OFFICE.

GLEN F. McCaughey, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed October 11, 1926. Serial No. 140,849.

This invention relates to the class of devices known as lifting jacks, and more particularly to a jack of the double extension type, designed to have an exceptionally long lift in proportion to its size and height when lowered or collapsed position.

While there are innumerable uses for such a jack, it is especially designed for use with the large size or balloon tires. For this use, it is desirable to have a jack which is compact and of small vertical height when lowered, in order to be placed under the low axle or other frame parts when the car is collapsed, and capable of a comparatively long lift to elevate the car above its normal driving height in order that the tire may be changed.

The jack is of that type employing a plurality of screws telescoping one within the other and each contributing its share to the total lift of the jack. A continuous rotation of the driving means will cause the screws to be successively and individually elevated or lowered, one at a time. According to the embodiment of the invention here shown, two nested screws are employed, the outer screw being an exteriorly threaded sleeve which meshes within a nut formed in the rotatable driving gear, which is supported in a hollow standard. The inner lifting screw, which supports the load at its upper end, meshes within a nut formed in the upper end of the outer screw sleeve. In the operation of this jack, the inner lifting screw will be held from rotation by its engagement with the load. At this time, if the outer screw sleeve is held against rotation, it will be elevated through the rotating driving nut, carrying the inner screw and load bodily upward with it. On the other hand, if the outer screw sleeve is permitted to rotate with the driving member, it will act as a nut to elevate the inner screw which carries the load.

This present invention is concerned more particularly with improvements in the means for controlling the rotary movements of the outer screw sleeve. The lower end of the sleeve is provided with projections which engage vertically extending ribs in the standard to hold the sleeve against rotation during its vertical travel, up or down, but these ribs terminate short of the upper and lower ends of the path of travel of the sleeve so that when at either of these ex-

tremities of its vertical movement the sleeve may rotate freely. In the annular path of rotation of the projections on the sleeve, at both the upper and lower ends of the standard, a spring stop device is provided which permits the free rotation of the projections in one direction, but prevents continued rotation thereof in the other direction. This stop device is in the form of a flat spring strip which projects diagonally into the path of travel of the projections so that when a projection is rotated in one direction it will push the spring strip out of its path and continue to rotate, but when rotated in the opposite direction, it will engage the end of the spring and be held from further rotary movement. This will force the screw sleeve to move vertically through the driving member, and after the projection has moved beyond the spring, it will, after a short angular movement, come into engagement with one of the vertical guide ribs in the standard which prevents further rotation of the sleeve during its vertical travel through the standard.

The general object of the invention is to provide a jack operating as briefly noted above and as set forth in more detail hereinafter.

Another object is to provide novel means for permitting rotation of the outer screw sleeve in one direction, when at the upper limit of its travel, and in the opposite direction when at the lower limit of its travel, while preventing rotation of this screw sleeve at all other times.

Another object is to provide a novel spring stop device for insuring the proper reengagement of the projections on the sleeve with the guide ribs in the standard, when direction of movement of the lifting members is reversed.

Other objects and advantages of the invention will be readily apparent from the following detailed description of certain approved forms of the apparatus.

In the accompanying drawings:

Fig. 1 is a central vertical section through the jack, showing the outer screw at the upper limit of its travel, and the inner screw partially elevated.

Fig. 2 is a horizontal section, on a somewhat larger scale, taken substantially on the line 2-2 of Fig. 1.

Figs. 3, 4 and 5 are sectional views, simi-

2
lar to Fig. 2, showing alternative forms of the spring stop mechanism.

Referring first to Figs. 1 and 2, the stationary standard for the jack comprises a substantially cylindrical hollow casting 1, having a broad supporting base 2. Near its upper end the standard has an inner annular supporting ring or flange 3, and above this a housing 4 partially encloses the driving mechanism hereinafter described. One member 5 of the raceway for the ball-bearing 6, rests upon the flange 3, while the other member 7 of the raceway supports the rotatable nut 8 which is formed integral with the hub of driving beveled gear 9. A short stub shaft 10, journaled in an extension 11 of the housing 4, carries at its inner end a driving beveled pinion 12, which meshes with the beveled driving gear 9. The outer end of shaft 10 is provided with a socket 13 to cooperate with any suitable form of removable handle, whereby the jack may be operated from a distance. It will be noted that the shaft 10 tilts upwardly so that the operator's end of the handle will be elevated to a convenient position.

Since the driving nut 8 supports the lifting screws (hereinafter described) which in turn support the load, the entire load will always be transmitted to the standard 1 through the anti-friction bearing 6, and in this way the lifting or driving strain will be reduced to a minimum.

The outer screw 14 is in the form of a hollow sleeve exteriorly threaded to engage within the driving nut 8. Pins 15 and 16, inserted between the threads of screw 14 at suitable points, or other equivalent means, engage the bottom and top faces, respectively, of nut 8 to limit the upward and downward travel of the outer screw 14. An inner screw 17, threaded in the same direction as screw 14, engages within a nut 18 formed in the upper end of the screw sleeve 14. A load-supporting cap 19, preferably provided with an upper roughened load-engaging surface 20, is mounted upon the upper end of inner screw 17.

A pin 21 is secured through the lower end of screw sleeve 14, and the projecting ends 22 of this pin are adapted to engage with the vertical guide ribs 23, preferably cast integral with standard 1 and projecting into the vertical cylindrical bore thereof. A single rib 23 and projection 22 would be sufficient, but it is preferable to have two diametrically opposed sets, as here shown. The ribs 23 terminate short of the upper and lower ends of the path of travel of the pin 21 so that when the projections 22 have passed beyond the ends of the ribs, the pin 21 and sleeve 14 can rotate freely within the annular spaces 24 and 25 provided in the respective ends of the standard for that purpose. In the specific forms of the inven-

tion shown in Figs. 1, 2 and 3, the portions 24 and 25 of the cylindrical bore of the standard are made somewhat larger, or of greater diameter, than the main central portion of the bore so as to provide annular grooves for the reception of the spring members hereinafter described.

In the form of the invention shown in Figs. 1 and 2, a strip of flat spring material 26 bent into substantially annular form, is housed within the upper enlargement 24 of the bore of the standard. One end portion of this spring strip extends diagonally inward, as at 27, into the path of rotation of the projections 22, and is then bent radially outward, as at 28, the end of the strip extending through an aperture 29 in the wall of the standard. The opposite end 30 of the spring strip 26 is bent outwardly into the aperture 29 to lock the annular spring 26 against rotation, within the housing 24. It will be noted in Fig. 2 that as the pin 21 rotates in a counterclockwise direction, as indicated by the arrow, the projections 22 will successively engage the diagonal portion 27 of the spring and push it outwardly as indicated in dotted lines, the radial end portion 28 extending out at this time through the aperture 29. When the projection 22 has passed by, the spring will snap back to its solid line position. Therefore, the spring device will not interfere with the continuous rotary movement of the projections 22 and sleeve 14 in this direction. However, if the direction of rotation is reversed so that the projections 22 move in a clockwise direction, as seen in Fig. 2, one of the projections 22 will engage the radial portion 28 of the spring, and further rotation of the sleeve 14 in this direction will be prevented.

A slightly modified form of spring is shown in Fig. 3. One end portion 32 of this spring extends diagonally into the path of rotation of the projections 22 similarly to the portion 27 of the first described modification, but the radial portion 28 of the spring is omitted. The opposite end of the annular spring is punched outwardly, as at 33, into an opening 34 in the wall of the standard to hold the spring device against rotation. The operation of this modified form is substantially the same as that of the form first described. When the projections 22 are rotated in a clockwise direction, one of them will engage the end 35 of the spring 32 and be held against further rotation. In the modification shown in Fig. 4, a short spring 36, corresponding to the portion 32 of the spring shown in Fig. 3, has its outer end 37 anchored by means of rivets 38 or similar devices, in an enlargement or recess 39 at one side of the standard. The spring member 40, shown in Fig. 5, is similar to the spring 36 shown in Fig. 4, with the excep-

tion that one end 41 of this spring extends outwardly through an opening 42 in the wall of the standard, and is anchored to the standard by screws 43 or equivalent devices.

- 5 A spring device exactly similar to any one of the forms hereinabove described is located within the annular space 25 at the lower end of the standard, but this spring device is reversed, that is, extends in the opposite direction to those shown in Figs. 2 to 5, respectively. The reason for this will be apparent from the description of the operation which follows.

Now describing the general operation of the jack, we will first assume that the operating crank is being rotated in a clockwise direction and that the lifting screws have started upward to elevate the load. At this time the inner screw 17 will be completely housed within the outer screw sleeve 14, and since the driving nut 8 is rotating in a counter-clockwise direction, as seen from above, it will tend to rotate the screw sleeve 14 in the same direction. However, the projecting ends 22 of pin 21 will engage the ribs 23 (as indicated in dotted lines in Fig. 2) and further rotation of the sleeve 14 will be prevented. Thereafter the rotation of nut 8 will cause the screw 14 to be elevated thereby, carrying bodily upward with it the inner screw 17 and the load supported thereby. When the sleeve 14 has reached the upper limit of its travel, and the pin 15 has engaged against the lower side of nut 8, the projection 22 will have passed above the upper ends of the ribs 23 (as shown in Fig. 1), and are now permitted to rotate freely in a counter-clockwise direction, the nut 8 and sleeve 14 rotating as a unit. The projections 22 will successively engage the diagonal portion 27 of the spring stop mechanism, but will merely push this spring out of their path, as indicated in dotted lines at the lower portion of Fig. 2. Since the inner screw 17 is held from rotation by the load supported thereon, the rotating nut 18 in the upper end of sleeve 14 will cause the inner screw and the load to be elevated, until the stop pin 45 in the lower end of screw 17 engages the lower end of nut 18, thus preventing complete disengagement of the two screws.

In order to lower the jack, the operating crank is rotated in the opposite or counter-clockwise direction. This will cause the driving nut 8 to be rotated in a clockwise direction, as seen from above, or as seen in Figs. 2 to 5, respectively. A partial rotation of the pin 21 will bring one of the projecting ends 22 into engagement with the abrupt end 28 or 35 of the spring, thus preventing further rotation of the projections in this direction, and consequently prohibiting further rotation of the sleeve 14 in unison with nut 8. This will cause the sleeve to be low-

ered through the rotating nut until the projection 22 has passed beneath the end of the stop spring. The sleeve 14 and pin 21 will now make a partial rotation, until the projecting ends 22 of the pin have come into engagement with the guide ribs 23 which again prevent further rotation of the sleeve. The sleeve 14 will now be lowered through the standard until the projecting ends 22 of pin 21 have passed beyond the lower ends of the ribs 23 into the annular recess 25. The sleeve 14 will now be permitted to rotate with the driving nut 8, in a clockwise direction, thereby lowering the inner screw 17 into the screw sleeve so long as this screw 17 is held from rotation by the load thereon, or by any other means. As noted hereinabove, the spring detent or stop device which is located in the lower recess 25 is disposed oppositely to the one illustrated in Fig. 2 so that the pin 21 may rotate freely in a clockwise direction, but is prevented from rotating in a counter-clockwise direction. When the direction of rotation of the operating crank is again reversed, so as to elevate the jack, this spring 26 in the lower recess 25 will function to prevent rotation of the pin 21 and sleeve 14 in a counter-clockwise direction until the sleeve has moved up far enough for the projections 22 to engage with the ribs 23, after which the operation is as first described hereinabove.

A jack of this double screw type might be operated, under favorable conditions, if the spring detents which form the particular subject matter of this invention were omitted. In such case, however, there would be no certainty as to the respective order of movements of the two screws, either of which might go up or down first, according to the friction between the different parts. The sleeve 14 might start to move vertically at any time, and there is always the possibility that the projections 22 will jam against the upper or lower ends of the ribs 23, thus locking the parts and preventing further operation of the jack. The spring stop devices insure a definite order of movements, compelling the screw sleeve 14 to move up or down first in either direction, and furthermore the spring stops are so located that the pin 21 and projections 22 will be stopped when out of vertical alignment with the ribs 23, thereby avoiding any possibility of jamming and consequent disabling of the jack. These spring devices are simple and easy to manufacture and install, and do not appreciably increase the bulk of the jack. The springs used in the upper and lower ends of the jack standard are identical in construction, being merely installed in reversed positions at the two ends of the jack.

The invention claimed in this application is limited to a lifting jack comprising the novel spring means herein disclosed for con-

trolling the rotation of the outer screw sleeve, or such modifications thereof as come within the scope of the following claims. This type of jack is more broadly claimed in 5 the copending applications of Walker et al., Serial No. 740,958, filed October 1, 1924 for lifting jack; and Johnson, for screw jack, Serial No. 750,231, filed November 17, 1924.

I claim:

- 10 1. In a lifting jack comprising a standard and a member rotatable therein, means for controlling the rotation of this member comprising a projection on the member, and a spring strip secured to the standard and extending diagonally into the path of rotation of the projection.
- 15 2. In a lifting jack comprising a standard and a member rotatable therein, means for controlling the rotation of this member comprising a projection on the member, and an annular spring strip mounted in the standard and having a portion extending diagonally into the path of rotation of the projection so that it will be pushed aside when the projection rotates in one direction but will prevent rotation of the projection in the opposite direction.
- 20 3. In a lifting jack comprising a standard and a lifting member capable of either vertical or rotary movements in the standard, means for controlling the movements of the lifting member, comprising a projection on the member, a substantially vertical guide rib in the standard, adapted to be engaged by the projection to prevent rotation of the member, and a spring strip secured to the standard beyond the end of the rib out of vertical alignment therewith and extending diagonally into the path of rotation of the projection to permit rotation of the projection and member in one direction only.
- 25 4. In a lifting jack comprising a standard and a lifting member capable of either vertical or rotary movements in the standard, means for controlling the movements of the lifting member, comprising a projection on the member, a substantially vertical guide rib in the standard adapted to be engaged by the projection to prevent rotation of the member, and an annular spring strip mounted in the standard and having a portion extending diagonally into the path of rotation of the projection so that it will be pushed aside when the projection rotates in one direction but will prevent rotation of the projection in the opposite direction.
- 30 5. In a lifting jack, a hollow standard, and lifting mechanism supported by the standard and including a screw movable vertically through the standard, and mechanism for controlling the rotation of the screw comprising a projection on the screw, a substantially vertical guide rib in the standard, the projection being adapted to move vertically beyond the end of the rib at which time it may rotate freely in one direction, and a spring strip projecting diagonally into this path of rotation of the projection to prevent continued rotation of the projection in the opposite direction.
- 35 6. In a lifting jack, a hollow standard, and lifting mechanism supported by the standard and including a screw movable vertically through the standard, and mechanism for controlling the rotation of the screw comprising a projection on the screw, a substantially vertical guide rib in the standard, the projection being adapted to move vertically beyond the end of the rib at which time it may rotate freely in one direction, and a spring strip secured at one end to the standard and projecting diagonally into the path of rotation of the projection, the strip yielding to permit the projection to pass in one direction, but the free end of the strip engaging the projection to prevent continued rotation in the other direction.
- 40 7. In a lifting jack, a hollow standard, and lifting mechanism supported by the standard and including a screw movable vertically through the standard, and mechanism for controlling the rotation of the screw comprising a projection on the screw, a substantially vertical guide rib in the standard, the projection being adapted to move vertically beyond the end of the rib at which time it may rotate freely in one direction, and an annular spring member mounted in the standard about the path of rotation of the projection and having a portion projecting diagonally into the path of the projection.
- 45 8. In a lifting jack, a hollow standard, a rotatable driving member, a pair of telescoping lifting screws, the outer screw being threaded within the rotatable driving member, a projection at the lower end of the outer screw, a guide within the standard for engaging the projection and preventing continued rotation of the screw while moving vertically, the guide terminating short of one end of the standard whereby the screw may rotate in one direction when the projection has passed beyond the guide, and means to stop rotation of the projection in the opposite direction when out of vertical alignment with the guide comprising a flat spring projecting diagonally into the path of rotation of the projection.
- 50 9. In a lifting jack, a hollow standard, a rotatable driving member, a pair of telescoping lifting screws, the outer screw being threaded within the rotatable driving member, a projection at the lower end of the outer screw, a guide within the standard for engaging the projection and preventing continued rotation of the screw while mov-

ing vertically, the guide terminating short of one end of the standard whereby the screw may rotate in one direction when the projection has passed beyond the guide, and 5 means to stop rotation of the projection in the opposite direction when out of vertical alignment with the guide comprising a flat spring secured at one end to the standard and projecting diagonally into the path of 10 rotation of the projection.

10. In a lifting jack, a hollow standard, a rotatable driving member, a pair of telescoping lifting screws, the outer screw being threaded within the rotatable driving member, 15 a projection at the lower end of the outer screw, a guide within the standard for engaging the projection and preventing continued rotation of the screw while moving vertically, the guide terminating short 20 of one end of the standard whereby the screw may rotate in one direction when the projection has passed beyond the guide, and means to stop rotation of the projection in the opposite direction when out of vertical 25 alignment with the guide comprising an annular spring member mounted in the standard about the path of rotation of the pro-

jection and having a portion projecting diagonally into the path of the projection.

11. In a lifting jack, a hollow standard, a 30 rotatable driving member mounted in the standard, a pair of telescoping lifting screws, the outer screw being threaded within the rotatable driving member, a lateral projection on the lower end of the outer 35 screw, a substantially vertical guide rib in the standard engaged by the projection when moving vertically, the rib terminating short of one end of the standard whereby the projection may pass beyond the rib and rotate 40 freely in one direction, the bore of the standard being formed with an annular channel beyond the end of the rib, and an annular spring member mounted in this channel and having a portion projecting into the path of 45 rotation of the projection, this spring portion being formed with one diagonal face whereby the projection will push the spring member out of its path when rotated in one direction, and one abrupt face for stopping rotation of the projection in the opposite direction. 50

GLEN F. McCaughey.

- ing vertically, the guide terminating short of one end of the standard whereby the screw may rotate in one direction when the projection has passed beyond the guide, and 5 means to stop rotation of the projection in the opposite direction when out of vertical alignment with the guide comprising a flat spring secured at one end to the standard and projecting diagonally into the path of 10 rotation of the projection.
10. In a lifting jack, a hollow standard, a rotatable driving member, a pair of telescoping lifting screws, the outer screw being threaded within the rotatable driving member, a projection at the lower end of the outer screw, a guide within the standard for engaging the projection and preventing continued rotation of the screw while moving vertically, the guide terminating short 15 of one end of the standard whereby the screw may rotate in one direction when the projection has passed beyond the guide, and means to stop rotation of the projection in the opposite direction when out of vertical 20 alignment with the guide comprising an annular spring member mounted in the standard about the path of rotation of the pro- 25
- jection and having a portion projecting diagonally into the path of the projection.
11. In a lifting jack, a hollow standard, a rotatable driving member mounted in the standard, a pair of telescoping lifting screws, the outer screw being threaded within the rotatable driving member, a lateral projection on the lower end of the outer screw, a substantially vertical guide rib in the standard engaged by the projection when moving vertically, the rib terminating short of one end of the standard whereby the projection may pass beyond the rib and rotate freely in one direction, the bore of the standard being formed with an annular channel beyond the end of the rib, and an annular spring member mounted in this channel and having a portion projecting into the path of 30 rotation of the projection, this spring portion being formed with one diagonal face whereby the projection will push the spring member out of its path when rotated in one direction, and one abrupt face for stopping rotation of the projection in the opposite direction. 35
